Primary Examiner — Cynthia Ramirez(74) *Attorney, Agent, or Firm* — CRAMER PATENT & DESIGN, PLLC; Aaron R. Cramer(57) **CLAIM**

The ornamental design for a compost bin assembly, as shown and described.

DESCRIPTION

FIG. 1 is a top front right exploded perspective view for a compost bin assembly showing my new design;

FIG. 2 is a top rear exploded perspective view thereof;

FIG. 3 is a front exploded view thereof;

FIG. 4 is a rear exploded view thereof;

FIG. 5 is a left exploded view thereof;

FIG. 6 is a right exploded view thereof;

FIG. 7 is a top exploded view thereof;

FIG. 8 is a bottom exploded view thereof; and,

FIG. 9 is a perspective view of the compost bin assembly in an assembled configuration.

The broken lines in the figures show portions of the compost bin assembly which form no part of the claimed design.
